FILTERING APPARATUS

Gordon G. Allan, Detroit, Mich.

Application March 10, 1943, Serial No. 478,663

1 Claim. (Cl. 210—122.1)

(Granted under the act of March 3, 1883, as amended April 30, 1928; 370 O. G. 757)

The invention described herein may be manufactured and used by or for the Government for governmental purposes, without the payment to me of any royalty thereon.

The present invention pertains to a novel apparatus intended primarily for the removal of dye and lead compounds from gasoline.

In Army operations, as well as on other expeditions, gasoline is needed for cook stoves, blow torches, cleaning metal parts and for other similar purposes. The presence of fumes from leaded gasoline is a health hazard, particularly in connection with cook stoves where the food is liable to become contaminated. Moreover, the residue of combustion eventually clogs the apertures of the stove burners. The handling of leaded fluid for cleaning purposes is likely to injure the skin.

Accordingly, it becomes necessary to carry a supply of clear, unleaded gasoline in addition to the fuel for the motor vehicles. However, military regulations or other circumstances might disrupt or eliminate the supply of clear gasoline, and in such cases it would be desirable to filter the leaded gasoline.

The principal object of this invention, therefore, is to provide a suitable apparatus for this purpose. The copending application of Frederick E. Neef, Jr., Serial No. 483,348, filed April 16, 1943, discloses a filter material for removing the dye and the tetraethyl lead, the latter combining chemically with the material with great affinity. Briefly, this material is an activated clay and preferably a hydrated aluminum silicate activated with sulphuric acid.

The invention herein disclosed is directed more particularly to the mechanical structure for supporting the activated filter, the supply and receiving receptacles and the fluid connection among these parts. The incoming fluid is first collected in a pool and then permitted to percolate upward through the activated material. Similarly, it is collected in another pool above the material and withdrawn therefrom to the receiver. The supporting structure is preferably designed to carry standard five gallon army cans as the supply and receiving receptacles and to permit easy replacement thereof.

The invention is fully disclosed by way of example in the following description and in the accompanying drawing in which

Figure 1 is a side elevation of the apparatus;

Figure 2 is a vertical elevation at right angles to Figure 1;

Figure 3 is a plan view of one of the auxiliary filter plates;

Figure 4 is a longitudinal section thereof, on the line 4—4 of Figure 3.

Reference to these views will now be made by use of like characters which are employed to designate corresponding parts throughout.

The framework of the apparatus consists of a number of uprights 1, such as four angle strips secured together by external transverse angle irons 2 at the top and bottom and at suitable intermediate levels. At the upper level next below the upper ends of the uprights is formed an internal supporting structure 3 such as a frame of angle bars or a floor, for a purpose that will presently be described. Similarly, another such support 4 is provided at a lower level.

On the lower support 4 is mounted a filter unit including a closed receptacle 5 containing transverse filter plates spaced from the top and bottom and having the construction shown in Figures 3 and 4. Each such plate comprises a pair of metal plates 6 having a substantial number of coinciding apertures 7 and an intervening filter cloth 8. These parts are secured together by suitably placed bolts 9. Between the filter plate units is packed the activated filtering medium which, as previously indicated, may be a hydrated aluminum silicate, activated by heating or with sulphuric or hydrochloric acid. The filter unit may be inserted between the uprights 1, as may be seen in Figure 2.

On the upper support 3 is mounted a suitable receptacle 11 containing colored, leaded gasoline to be filtered. This may be a standard army five gallon container in inverted position so that the usual vent tube 12 is open at the upper end. The usual cap is replaced by another cap 13 from which extends a rather long pipe 14 having a pet cock 15. This pipe is connected to the lower end of the filter unit 5, at the space between the bottom and the lower plate unit 6—9.

A similar receptacle 16 is suitably supported beneath the filter unit. Both receptacles 11 and 16 are adapted to be inserted between the uprights 1, as may be seen in Figure 2. The cap 17 of the receptacle 16 is removed, and into the opening is inserted a pipe 18 extending from the upper end of the filter unit 5 or from the space between the top wall thereof and the upper plate unit 6—9. The tubes 14 and 18 are preferably flexible for ready manipulation in changing the receptacles and the filter unit.

In the operation of the device, the pet cock 15 is opened to permit gasoline to flow from the re-

ceptacle 11 to the bottom of the filter unit 5. From here the gasoline percolates upward through the filter body 5 and both plate units 6-9 and enters the space between the upper plate unit and the top of the receptacle 5 whence it flows into pipe 18 by which it is delivered to the lower receptacle 16. The rate of flow is adjusted at the petcock 15 in accordance with the contact time required for the complete filtration of the particular gasoline.

The filtration is a chemical action in which the tetraethyl lead combines very securely with the activated clay. Consequently this material loses its effectiveness in time and must be replaced. This is easily done on disconnecting the pipes 14 and 18.

Although a specific embodiment of the invention has been illustrated and described, it will be understood that various alterations in the details of construction may be made without departing from the scope of the invention as indicated by the appended claim.

What I claim is;

A filtering apparatus comprising in combina-

tion a frame, supporting means on said frame for holding three containers in vertically spaced relationship, a filtering unit comprising one of said containers positioned upon the intermediate supporting means, a pipe connected to the lower portion of the filtering unit and extending above the upper supporting means, a pipe connected to the upper portion of said filtering unit and extending below the intermediate supporting means, a similar plug connected to the end of each extended end of each pipe for connecting said pipes into similar containers positioned symmetrically above and below said filtering unit, said plugs being in substantially vertical alignment, and a pipe connected to the upper plug and opening into the upper interior of the container positioned upon the upper supporting means to vent said upper container, whereby liquid carried in the upper container will flow to the lower portion of said filtering unit and from the upper portion of said filtering unit to the lower container.

GORDON G. ALLAN.
